United States Patent Office.

AUSTIN KELLEY, OF BROOKLYN, NEW YORK.

Letters Patent No. 95,233, dated September 28, 1869; antedated September 16, 1869.

IMPROVEMENT IN RUFFLES.

The Schedule referred to in these Letters Patent and making part of the same.

To all whom it may concern:

Be it known that I, AUSTIN KELLEY, of Brooklyn, in the county of Kings, and in the State of New York, have invented a certain new and useful Improvement in Ruffles; and do hereby declare that the following is a full, clear, and exact description thereof, reference being had to the accompanying drawings, and to the letters of reference marked thereon, in which—

Figure 1 shows the fabric before made into ruffles, and

Figure 2 shows the same when made into ruffles.

My invention consists in producing ruffles from a woven fabric, so that when the article is finished it shall have a selvage wearing-edge.

Heretofore, in the manufacture of ruffles, particularly those machine-made, it has been the practice to form a wearing or lower exposed edge, by folding the fabric upon itself, and stitching the folded parts together, thus forming a double thickness of fabric at that portion of the article.

While this mode of manufacture enables the producer to use common, wide goods, by tearing the same into strips, the article is rendered objectionable for several reasons.

It is cumbersome in appearance, will not present a graceful edge, by reason of its being rendered stiff by the tightly-drawn stitches necessary to hold down the folded edge, and requires an additional operation to finish it, *i. e.*, the stitching or hemming of its edge, which must be done by mechanism distinct from that which folds and forms the ruffle proper. This additional operation renders the product expensive, and imposes the objection I have removed.

To enable others skilled in the art to make and use

my invention, I will proceed to describe its construction.

I first produce a woven fabric, of width suitable to form two ruffles, as shown in the drawings, it having selvage-edges.

This fabric is then introduced into a machine adapted to form a double ruffle, and is Shirred and sewn, as shown in fig. 2, after which it is divided in its centre longitudinally, and two ruffles, each having a selvage wearing-edge will be produced.

It is obvious that any quality, color, or material may be used to form the fabric of which my article is produced.

It will be further apparent that by the use of a fabric having its edge finished in its production, I am enabled to make a ruffle without the delay and expense of binding or hemming its edge, and produce an article with many excellencies not attainable by the present mode of manufacture.

I am aware that ruffles are woven complete which have a selvage-edge. This I do not claim; but

What I do claim, and desire to secure by Letters Patent, is—

As a new article of manufacture, a machine-shirred, crimped, or gathered ruffle, whether provided with a band or not, having a selvage-edge formed from a fabric, substantially as herein described.

In testimony that I claim the foregoing, I have hereunto set my hand, this 25th day of January, 1869.

AUSTIN KELLEY.
